CUSHIONING MECHANISM

George F. Vaia, Chevy Chase, Md., and Glenn F. Couch, Buffalo, N. Y., assignors to The Symington-Gould Corporation, Depew, N. Y., a corporation of Maryland

Application September 29, 1950, Serial No. 187,582

12 Claims. (Cl. 267—9)

1

This invention pertains to a cushioning mechanism and more particularly to a type thereof suitable for association with a group of bolster supporting springs in a railway truck.

An object of the invention is the provision of an improved cushioning mechanism wherein a plurality of shoes are urged radially by a plurality of springs.

A further object of the invention is the provision of an improved cushioning mechanism for use in a railway truck and wherein a constant frictional value is developed during an expansive and contractive action of the mechanism.

An added object of the invention is the provision of an improved cushioning mechanism wherein torsion springs are employed to urge shoes radially into frictional contact with a sleeve.

The above and numerous other objects of the invention will become apparent from the succeeding description taken into consideration with an exemplified form of the invention illustrated by the accompanying drawing: wherein,

Figure 1 is a vertical sectional view of an improved cushioning mechanism embodying the present invention.

Figure 2 is a horizontal sectional view taken along the lines 2—2 of Figure 1 looking in the direction of the arrows.

Figure 3 is a horizontal sectional view taken along the lines 3—3 of Figure 1 looking in the direction of the arrows.

Figure 4 is a horizontal sectional view taken along the lines 4—4 of Figure 1 looking in the direction of the arrows.

Figure 5 is a horizontal sectional view of an expanded portion of the cushioning mechanism before assembly with related portions thereof.

Referring now in detail to the drawing wherein like reference characters designate like parts, the numeral 1 is employed, in a somewhat general manner, to indicate a cushioning mechanism characteristic of the present invention. The descriptive term cushioning mechanism is used hereinabove in a somewhat general sense and, as will be appreciated by those skilled in the art to which this invention appertains, this descriptive term is synonymous with cushioning unit, snubber or friction unit, any of which may be hereinafter employed to designate the structure of the present invention. The snubber is primarily designed to be interposed between a bottom surface of a bolster or load carrying member designated by a diagrammatic line 2 in Figure 1 and a top surface of the side frame

member designated by a diagrammatic line 3 in Figure 1. These two surfaces are vertically spaced and therebetween, in combination with the friction unit, are a plurality of coil springs 5 (not shown) to carry or support yieldably the bolster on the side frame. As is well known, the snubber having a period of vibration different than that of the accompanying coil springs, the assemblage will form a non-harmonic group 10 exceedingly desirable in that the vibrations of the assemblage will not synchronize with periodic impulses to which the assemblage will be subjected in service.

The cushioning unit has a top or outer member or sleeve 4 formed by a crowned round cap 5 arranged to bear against and rock relative to the bolster bottom surface. The cap has a centralized, shouldered, instanding collar 6 projecting inwardly of the unit. The collar is desirably 15 annular or circular in configuration and extending thereabout and therefrom is a cylindrical, tubular casing or shell 7 which projects axially of the unit for an appreciable distance and presents an inner, cylindrical rubbing or friction face 8 for the purpose to be made hereinafter apparent. It is desirable to form the casing and the cap as two separate components since during assembly of these two parts the shell may easily and possibly more accurately be arranged in 20 true axial alignment of the unit. Various means 25 may be employed to secure or fasten these two sleeve parts together and toward this end it is preferred to scarf or cut the upper extremity of the shell on a sloping line 9 so that a well 30 will be formed for the deposit or presence of a continuous weld 10.

Associated with the sleeve are a plurality of shoes 11 presenting an assemblage or nest of cylindrical formation and each having a segmented, vertical, outer brushing or friction face 12 in complete bearing relation with a coextensive or contiguous portion of the shell or sleeve rubbing face. Each shoe has a lower foot or outstanding ledge 13 extending radially outwardly beyond a vertical or downward extension of the sleeve rubbing face. The feet of the multiple shoe assemblage presents an interrupted shelf upon which bears a ring or annular member 14 with the latter having therein a continuous circular undercut 15 to accommodate the shoe feet. Since the friction unit will, in service, be subjected to compressive forces a yieldable means is interposed between the sleeve and shoes so as to resist the compressive forces 55 and extend the unit. Such a yieldable means is

incorporated in the unit and is characterized by a coil or helical spring 16 extending around the shell in spaced relation thereto and bearing, at its opposite ends against the sleeve cap and shoe ring.

As previously stated the shoe assemblage is multipart and it is preferred, but not believed essential, that the number of the shoes be limited to three counterpart components. The portion of each shoe which carries the outwardly exposed brushing face may, for the sake of convenience or clarity, be classified as a stem or staff 17 and, as will be now apparent or obvious, any relative vertical movement of the shoes and sleeve will result in the creation of frictional retarding forces on the mating, brushing and rubbing faces. Many arrangements or means present themselves for the purpose of urging the shoe stems or staffs radially into constant bearing relation with the sleeve, however, in this instance, it is preferred to employ force or shoe actuating means of a number equal to the number of shoes employed. This phase of the construction is to be considered as an illustration only and not as a limitation. The force imparting means provided in the present structure is a plurality of springs 18 and more specifically classified as torsion springs because of the torque action thereof. In line with the above thought, the torsion springs are three in number and are arranged centrally of the unit in vertically spaced relation with the axes thereof in parallel relation with the axis of the unit. Each torsion spring is formed of a central winding or coil 19 terminating at its opposite ends in angularly disposed, re-entrant, legs 20 which function as end terminals of the central winding. The legs are preferably parallel and are arranged in outward spaced relation to the central winding. Also the legs of each torsion spring are extended in opposite directions since they emanate from the same central winding and they are preferably of a length equal to the axial length of the central winding so as to present members of appreciable length for the purpose to be made hereinafter apparent.

Each shoe stem is divided into a plurality of vertically arranged compartments 21—in the instant structure three compartments—and the compartments of the related shoes form vertically arranged cages 22. The compartments of each shoe staff are defined by inwardly directed circular ribs 23 which are suitably spaced vertically along the inside of the shoe stem. Accordingly, a torsion spring is positioned within each cage and is retained in a vertical or predetermined elevated position by the ribs forming barriers against which the legs may come into contact for preventing a vertical shifting of the torsion springs from illustrated position. Because of what may be considered as a toggle action of the torsion springs each shoe compartment is provided with a bed or concave seat 24 disposed centrally of the compartment and directed vertically between related or adjacent ribs. These beds or seats are for the accommodation of the spring legs and when the torsion springs are stressed as clearly illustrated in Figures 1 through 4 as opposed to the showing of Figure 5, the seat and leg associations not only prevent a turning movement of the torsion springs but also result in a centralized, concentrated, radial force urging the shoes radially into frictional engagement with the sleeve. Each torsion spring, having only two terminals or

legs but in a cage formed by three horizontally aligned compartments, is arranged to act only on two shoes and, as clearly illustrated by Figures 2 through 4 of the drawing, adjacent torsion springs have one leg each acting upon only one shoe in common, while the other leg of each torsion spring acts upon the other two shoes.

By way of further explanation the three mated shoes are designated by the characters X, Y and Z and the three torsion springs by the characters A, B, and C. One leg each of springs A and B act to urge only the shoe Y radially while the other leg of each of these springs acts upon the shoes X and Z. In like manner a leg each of springs B and C acts upon the shoe Z while the other legs of these springs act upon the shoes X and Y and so a leg each of springs A and C acts upon the shoe X while the other legs of these last named springs act upon the shoes Y and Z.

Generally considered, therefore, while one torsion spring may act only upon two adjacent shoes the assemblage is such that all of the torsion springs considered together act upon all of the shoes to expand the shoes radially into frictional contact with the sleeve.

From the above, it will be noted that various changes and alterations may be made to the illustrated and described construction without departing from the spirit of this invention or scope of the appended claims.

We claim:

1. In a cushioning unit, the combination of, a sleeve, a plurality of shoes arranged to frictionally engage said sleeve, spring means extending between said sleeve and shoes for urging them apart axially of said unit, and a plurality of torsion springs within said shoes, each of said torsion springs having a coil portion and end portions outstanding from said coil portion, said coil portions being spaced from and said end portions engaging said shoes for urging the latter radially of said unit into frictional engagement with said sleeve.

2. In a cushioning unit, the combination of, a sleeve, a multipart shoe arrangement extending into said sleeve, spring means acting axially of said unit for urging said sleeve and shoe arrangement in opposite directions, and a plurality of torsion springs each having ends outstanding from a coil portion thereof, said torsion springs acting on said shoe arrangement entirely through said ends for urging said shoe arrangement into frictional contact with said sleeve.

3. In a cushioning unit, the combination of, a sleeve, a plurality of shoes extending into said sleeve, spring means urging said sleeve and shoes in opposite directions axially of said unit, and a plurality of torsion springs each having outstanding legs extending substantially parallel to an axis of said unit and bearing against a pair of said shoes for urging the latter into frictional engagement with said sleeve.

4. In a cushioning unit, the combination of, a sleeve, a plurality of shoes extending into said sleeve, resilient means outwardly of said sleeve for urging said sleeve and shoes apart axially of said unit, a plurality of torsion springs having coils spaced vertically from one another, and each coil having radially spaced legs directed substantially parallel to an axis of said unit and bearing against a pair of said shoes for urging the latter into frictional engagement with said sleeve.

5. In a cushioning unit, the combination of, a sleeve, a plurality of shoes extending into said

sleeve, resilient means outwardly of said sleeve for urging said sleeve and shoes apart axially of said unit, a plurality of torsion springs within said shoes; each torsion spring having a coil with an axis parallel to an axis of said unit, and each coil terminating in oppositely directed legs bearing radially against a pair of said shoes for urging the latter radially into frictional contact with said sleeve.

6. In a cushioning unit, the combination of, a sleeve, a plurality of shoes extending into said sleeve, resilient means outwardly of said sleeve for urging said sleeve and shoes apart axially of said unit, a plurality of torsion springs within said shoes and having coils in vertical spaced relation, each torsion spring coil having oppositely directed legs bearing against a pair of said shoes for urging the latter into frictional contact with said sleeve.

7. In a cushioning unit, the combination of, a sleeve, a plurality of shoes extending into said sleeve, resilient means outwardly of said sleeve for urging said sleeve and shoes apart axially of said unit, a plurality of torsion springs within said shoes and having axes substantially parallel with an axis of said unit, each of said torsion springs having a coil with oppositely directed legs bearing radially against a pair of said shoes for urging the latter into frictional contact with said sleeve.

8. In a cushioning unit, the combination of, a sleeve, a plurality of shoes extending into said sleeve, resilient means outwardly of said sleeve for urging said sleeve and shoes apart axially of said unit, a plurality of torsion springs within said shoes, each torsion spring having a coil with an axis parallel to an axis of said unit, seats in said shoes, and reentrant legs on said coils bearing radially of said unit against said seats for urging said shoes into frictional contact with said sleeve.

9. In a cushioning unit, the combination of, a sleeve, a plurality of shoes extending into said sleeve, resilient means outwardly of said sleeve for urging said sleeve and shoes apart axially of said unit, a plurality of separated torsion springs within said shoes and having axes extending longitudinally and vertically of said unit, each

torsion spring having a coil spaced inwardly of said shoes, and terminal legs formed on each coil and in bearing relation with adjacent shoes for urging the latter into frictional contact with said sleeve.

10. In a cushioning unit, the combination of, a sleeve, a plurality of shoes extending into said sleeve, resilient means outwardly of said sleeve for urging said sleeve and shoes apart axially of said unit, a plurality of separated torsion springs within said shoes, each torsion spring having a coil spaced inwardly of said shoes, terminal legs on each coil and bearing against related shoes for urging the latter into frictional contact with said sleeve, and means on said shoes for holding said torsion springs separated axially of said unit.

11. In a cushioning unit, the combination of, a sleeve, a plurality of shoes extending into said sleeve, resilient means for urging said sleeve and shoes apart axially of said unit, and a plurality of torsion springs within said shoes, said springs being separated axially of said unit and each of said springs bearing against a different pair of said shoes for urging said shoes into frictional contact with said sleeve.

12. In a cushioning unit, the combination of, a sleeve, a plurality of shoes extending into said sleeve, resilient means for urging said sleeve and shoes apart axially of said unit, and a plurality of torsion springs within said shoes, each of said springs acting on a different pair of said shoes for urging said shoes into frictional contact with said sleeve.
